TIMER AND DISTRIBUTER FOR ELECTRICAL IGNITION PURPOSES.

1,123,121.

Specification of Letters Patent.

Patented Dec. 29, 1914.

Application filed March 26, 1913. Serial No. 756,869.

To all whom it may concern:

Be it known that I, JAMES B. FRAWLEY, a citizen of the United States of America, residing at Pittsfield, in the county of Berkshire and State of Massachusetts, have invented new and useful Improvements in Timers and Distributors for Electrical Ignition Purposes, of which the following is a specification.

10 This invention relates to improvements in timers and distributors for ignition systems. The object of the invention is to provide a device for maintaining the high tension distributor cables which carry the spark 15 current to the spark coils in a stationary and fixed position. Heretofore, in devices where the cables are constantly being moved when the timing mechanism is operated, they soon work loose, causing inefficient ignition and operation of the internal combustion engine.

20 The invention, in general, comprises a hollow open-ended casing-member (preferably made of insulating material of high 25 resistance and having metallic insert pieces therein to which the high tension cables are secured, as by soldering), a spark-current distributor disk located within this casing and adapted to be rotated past the inner 30 ends of the high tension cables, and a make-and-break device that is adjustable with relation to the fixed casing for advancing or retarding the time that the primary circuit is opened and the occurrence of the 35 spark at the spark plugs.

In the drawings,—Figure 1 is an end 40 elevation, looking toward the end of the device to which the cables are secured, and also showing, in dotted lines, the distributor 45 for conveying the high-tension current of the coil or magneto to the individual cables; also illustrating, partly in full lines and partly in dotted lines, the make-and-break device for the primary circuit,—the 50 full lines representing one position and the dotted lines a different position of the timer mechanism. Fig. 2 is a sectional view taken through the axis of the cam-shaft and showing the interior construction of the 55 distributor mechanism; also the make-and-break device in the primary circuit.

Referring to the drawings in detail,—*a* 60 designates the fixed casing to which is rigidly secured, as by shrinking or a driving

fit, the bracket-member *b* that is formed 55 with openings *c* therein for attaching it to a fixed support on the engine or other suitable framework. Secured to the fixed member or casing *a* is a hollow, open-ended, cup-shaped member *d* formed of hard rubber or other suitable insulating material and suitably secured to the member *a*, as by screws *d'*. This member is usually made of molded insulating material of very high 60 resistance, and secured within the end portion thereof is a cup-shaped piece *e* that is 65 interiorly threaded to receive the perforated threaded terminal fitting *f* and to which the core *g* of the cable *h* is secured. Extending 70 into the space *i* within the member *d* is the 75 terminal *j* that is in electrical connection with the wire *g* of the cable *h*.

k designates the distributor disk of insulating material having a plate *m* secured thereto. This plate conveys the high-tension 80 spark currents from the cable *o*, which is the high tension cable from the secondary coil of a spark coil,—the current being 85 conveyed to the distributor *k* by means of the carbon brush *p* which is always in contact with the plate *m*, being normally forced against the same by means of a spring *q*; and it will be seen that when the shaft *r* is 90 rotated the spark-current will be successively distributed by means of the plate *m* to the four distributor cables *h* that lead to the several spark plugs, in the well-known manner.

s designates a recessed casing-member 95 that is loosely mounted for movement through a small arc upon a turned portion *a²* of the member *a*, and within this casing-member are carried the make-and-break devices for the primary circuit and indicated by the letters *t* and *u*, and the contacts *v* 100 and *w* thereon.

x designates the make-and-break cam on the shaft *r* and *y* the roller on the inner 105 end of the lever *t*. When the shaft *r* is rotated, the cam *x* causes the lever *t* and its contact *v* thereon to be moved against the contact *w*, which will close the circuit in the primary winding of the coil in the usual manner. The lever *t* is pivotally mounted on a pin 3 within the recess 3¹ of the casing 110 *s* and is normally held against the cam *x* by means of the coil spring 4. The casing *s* which contains the make-and-break mech-

anism is adapted to be moved by means of a suitable connection s^2 extending from the casing s into the dotted-line position s' by means of the connection s^2 , to vary the time 5 of the currents of the spark in the secondary circuit. The casing s is formed with an opening or slot 5, and a pin 6 which is secured to the casing a enters the same, whereby the movements of the timer device 10 and its casing may be limited. The recess or chamber 3^1 is adapted to be closed by means of a plate s^3 , as shown at s^4 , whereby access can readily be had to the contact points v and w .
15 The inner ends of the cables h pass through collars d^2 that are threaded to the projections d^3 . These collars serve to rigidly retain the ends of the cables h in place as they engage the outer side of the 20 cables, as clearly shown.
It will be seen from this construction that the casing a and the cables h always remain in a fixed and permanent position while the timer device is movable thereon 25 and relative thereto, as desired. The cam x is carried by the shaft r to which the distributor k is secured by means of the plate 7, and this shaft is preferably mounted in ball-bearing devices conventionally 30 indicated at 8.

What I claim, is,—

1. In a spark-current timer and distributor-device for ignition systems, the combination, of a casing member, means to secure the member to a fixed support, distributor cables secured to the fixed casing member, a rotating member to convey the spark-current to the distributor cables, a recessed timer casing-member mounted for 35 movement through a small arc on the fixed casing, a make-and-break device carried by the recessed casing and located therein, a 40

cam element on the distributor-shaft to open and close the make-and-break device, all constructed and arranged to permit the 45 occurrence of the spark current to be varied without moving the cables which carry the spark-current, as described.

2. In an electrical timer and distributor for ignition systems designed to retain the high-tension cables in a fixed position, the combination, of a fixed member to which said cables are secured, a distributor-plate rotatably mounted in the fixed-member to convey the spark-current to said cables, a 55 second casing-member having a recess therein, make-and-break devices located in the recessed portion of the second casing-member, said second member being mounted for movement through an arc on the first-mentioned casing-member to vary the time of making and breaking the contacts by said devices to vary the time of making and breaking the spark in the spark-current, and means to operate the make-and-break 60 devices, as described.

3. In an electrical timer and distributor for ignition systems, designed to retain the high tension conductors in a fixed position, the combination with a fixed casing member, of a segmental conducting plate, rotatably mounted in said casing member, a conductor in contact with said plate other conductors distributed in the path of said plate, a second casing, pivoted to said first named casing and adapted for limited relative movement thereto, make and break devices located in said second casing, a shaft, and a cam on said shaft for operating said make and break devices, as described.

JAMES B. FRÄWLEY.
